UNITED STATES PATENT OFFICE.

ALBERT R. PRITCHARD, OF ROCHESTER, NEW YORK.

LANTERN.

No. 809,462.

Specification of Letters Patent.

Patented Jan. 9, 1906.

Application filed September 22, 1905. Serial No. 279,607.

To all whom it may concern:

Be it known that I, ALBERT R. PRITCHARD, a citizen of the United States, and a resident of Rochester, in the county of Monroe and State of New York, have invented certain new and useful Improvements in Lanterns, of which the following is a specification.

This invention relates to improvements in lantern, and has for its object to provide a construction whereby the principal constituent parts of the lantern can be stamped out separately and then connected together by interlocking parts, thus obviating the use of solder.

15 In the drawings, Figure 1 is a completed lantern in elevation. Fig. 2 is a central vertical section, and Fig. 3 shows a detail of construction.

The lantern shown in the drawings to illustrate my novel construction comprises a font 1, a burner 2, tubes 3, connecting with the air-chamber 4 and burner-cap 5, whose several functions are well understood and which have the form and relative positions common in tubular lanterns of this type. The font 1 is stamped up in the usual manner, but with a circumferential flange 6 extending out from its lower edge and at right angles thereto and a similar flange 7 around the 30 opening for the reception of the air-chamber and burner, that is directed downwardly.

The air-chamber 4 is formed by stamping a bell-shaped piece whose lower edge 8 is adapted to enter the font and lies close against the flange 7. The burner-cone 9 is adapted to fit within the air-chamber and to extend down into the font, at the same time lying close to its lower edge 8. Suitable dies are now employed to bend up and roll back 40 upon each other the flange 7 and edges 8 and 9 in the manner shown in Fig. 2. In this way these three parts are locked together mechanically by a simple operation and without the use of solder. Afterward the bottom 10 of the font is made of such size that it lies beneath the horizontal flange 6 at the base of the font. A shoulder 11 may be struck up from the bottom 10 just within the flange 6. (See

Fig. 3.) The flange 6 and so much of the bottom as lies below it are bent up and rolled back in the manner shown in Fig. 2 by means of tools suitable for that purpose, thus making a tight connection between said parts.

It is clear that by the construction above described the holes in the air-chamber 4 for the ends of the air-tubes 3 may be brought into registry with the top edge of the font 1, so that the air-tubes may lie exactly upon said font, and yet the holes for the air-chamber may be punched at a reasonable distance 60 from the end of the manufactured air-chamber, and that in rolling together the flange 7 of the font and the edge 8 of the air-chamber the registry above mentioned may be produced and maintained accurately. In rolling together the edges 7 and 8 it is clear that the air-chamber 4 will be pulled downward, so that the said registry will be produced.

What I claim is—

1. The combination of a font having an 70 opening in its upper surface provided with a downwardly-turned flange, and an air-chamber having an edge fitting within and against said flange and provided with side openings for the air-tubes of the lantern, the said two 75 edges being rolled together whereby the said side openings are brought into registry with the top of the font when the said two edges are rolled together.

2. The combination of a font having an 80 opening in its upper surface provided with a downwardly-turned flange, an air-chamber having an edge fitting within and against said flange and provided with side openings for the air-tubes of the lantern, the said two 85 edges being rolled together whereby the said side openings are brought into registry with the top of the font when the said two edges are rolled together, and a burner-support 90 having an edge rolled in with the edges of the font and of the air-chamber.

ALBERT R. PRITCHARD.
